UNITED STATES PATENT OFFICE

2,227,455

HAMMER

John Thorne Lane, Los Angeles, Calif.

Application October 5, 1938, Serial No. 233,435

1 Claim. (Cl. 145—30)

My invention relates generally to hammers and more particularly to means formed on the sides of the main body of the hammer for receiving and holding nails, brads, tacks, and the like, 5 while the same are being initially set or started in the work in which they are subsequently driven.

In various lines of work where hammers are used, it frequently happens that it is necessary to 10 drive nails and tacks at elevated points that can not be conveniently reached by both hands of the workman, one hand being used to hold the nail or tack and the other hand to manipulate the hammer.

15 This condition is encountered by carpenters and other workmen engaged in the erection of buildings, also by persons engaged in nailing or tacking signs, advertising cards, and the like, on walls, posts, and the like, and, it is the principal 20 object of my invention to provide a hammer having grooves formed in its side faces for the reception of the heads of nails, brads, tacks, and the like, so as to conveniently hold the same while the points thereof are being set or initially 25 driven.

A further object of my invention is, to construct 30 and shape the head receiving grooves in the sides of the hammer so that they will conveniently receive the heads of nails, brads, tacks, and the like, and maintain the latter in practically straight positions extending outwardly at right angles from the side faces of the hammer and which provision greatly facilitates the setting or 35 initial driving operations.

40 A further object of my invention is, to construct the nail or tack head receiving groove in the side of the head of the hammer so as to effectually prevent the swinging or dropping movement of the nail into an inclined position and, which condition it will be understood interferes to a large extent and in some instances precludes the possibility of imparting the initial drive or 45 setting of the nail or tack.

45 With the foregoing and other objects in view, my invention consists in certain novel features of construction and arrangement of parts that will be hereinafter more fully described and claimed and illustrated in the accompanying drawing in which:

50 Fig. 1 is a side elevational view of a hammer head constructed in accordance with my invention and which head is positioned on a conventional handle.

55 Fig. 2 is a plan view of the hammer head.

Fig. 3 is an enlarged vertical section taken on the line 3—3 of Fig. 1.

Fig. 4 is an enlarged detail section taken on the line 4—4 of Fig. 1.

Fig. 5 is an enlarged detail section taken on the line 5—5 of Fig. 1.

Fig. 6 is a plan view of a modified form of the hammer head.

Referring by numerals to the accompanying drawing, 10 designates the main body portion of 10 the hammer, which body portion is provided with a vertically disposed aperture 11 for the reception of the end of a handle 12 and driven into the end of the handle that occupies the aperture 12 is a conventional wedge 13 that functions to 15 expand the end of the handle 12 into the aperture 11 and thereby secure the hammer head on the handle.

Projecting forwardly from the body 10 is a short cylindrical body 14, the outer portion of 20 which may be slightly enlarged in diameter and the front surface 15 of this enlarged portion serves as the hammer face. The side of the body of the hammer opposite the outwardly projecting body may be provided with a pair of conventional 25 curved or inclined claws utilized for pulling nails and the like, but I prefer to mount on this side of the hammer body a pair of separately formed jaws 16 that are pivoted to the hammer body by a transverse pin or screw 17 and which pivoted 30 jaws are of the type disclosed in U. S. Letters Patent No. 2,026,581 issued to me January 7, 1936, on Claw bar.

35 Formed in the side faces of the body 10 are vertically disposed grooves 18 which gradually decrease in width toward their lower ends and said grooves being substantially dovetail in horizontal section. In addition to decreasing in width toward their lower ends, these grooves decrease in depth from top to bottom and as a result of 40 such construction, the inclined bottom surface 20 of each groove terminates with the lower ends of the inclined side surfaces 21 of the groove at a point on the lower portion of the external side face of the body of the hammer.

45 Thus, when the heads of nails, brads, tacks, or the like, of different sizes are positioned in the groove 18, they will automatically pass downwardly therein until the edges of the heads make contact with the inclined bottom and side surfaces of the groove and said nails, brads, or tacks, will be held in positions substantially at right angles to the side face of the hammer and in which positions they may be conveniently set or initially driven. After being set, the hammer is 55

drawn downward so that the same is disengaged from the nail, brad, or tack, and the latter is now driven under the force of the blow struck by the face 15 of the hammer.

5 In the construction illustrated in Figs. 1 to 5 inclusive, the tapered nail head receiving grooves 18 are formed directly in the side portions of the body of the hammer and, in Fig. 6 I have shown a modified construction wherein 10 hardened metal inserts 22, each provided with a tapered nail head receiving groove 23 that is practically identical with the groove 18, are seated in dovetail grooves 24 that are formed in the side faces of the body 10 of the hammer. These 15 grooved inserts may be rigidly secured to the body of the hammer by welding or otherwise.

Thus it will be seen that I have provided a hammer having tapered nail head receiving grooves in its side faces and which hammer is

relatively simple in construction, inexpensive of manufacture and very effective in performing the functions for which it is intended.

Obviously, minor changes in the size, form and construction of the various parts of my improved 5 hammer, may be made and substituted for those herein shown and described, without departing from the spirit of my invention, the scope of which is set forth in the appended claim.

I claim as my invention:

A hammer head provided in the side face of its body with an undercut groove that gradually decreases in depth toward its lower end, the side faces of which groove are inclined in opposite directions, the width of which groove gradually decreases toward its lower end and the lower end of which groove is pointed and terminates on the side face of the body of the hammer head. 15

JOHN THORNE LANE.
